UNITED STATES PATENT OFFICE.

DE FOREST P. FULLER, OF DENVER, COLORADO.

ELECTRIC IGNITING DEVICE FOR GAS-BURNERS.

1,178,510.

Specification of Letters Patent. Patented Apr. 11, 1916.

Application filed March 12, 1915. Serial No. 14,023.

To all whom it may concern:

Be it known that I, DE FOREST P. FULLER, a citizen of the United States of America, residing at the city and county of Denver and State of Colorado, have invented a new and useful Electric Igniting Device for Gas-Burners, of which the following is a specification.

This invention relates to improvements in electric igniting means for gas burners, and more particularly the gas burners of cooking ranges.

The object of the invention is to provide a sparking device in connection with a gas burner, which is operated simultaneously with the admission of gas to the burner and by the gas admitting means. Further, to provide an electric sparking device in connection with a gas burner, comprising a fixed and a movable spark point in circuit with a source of power, the said movable point being operated by the turning of the stem of the gas valve to bring it in contact with the fixed point to produce a spark whereby the gas is ignited, the said movable point being automatically restored to its normal position immediately after the spark is produced. Further, to provide an electric sparking device of this character which is simple in construction and which can be easily applied to burners as at present constructed. These objects are accomplished by the mechanism illustrated in the accompanying drawings in which:

Figure 1 is a plan view illustrating the supply pipe and two burners such as are used upon the ordinary gas ranges in connection with the improved igniting device, one of the burners being partly broken away. Fig. 2 is a side or edge view of one of the burners with the sparking device secured thereto. Fig. 3 is a vertical sectional view through the burner and longitudinally through the sparking or igniting device, which is connected therewith. Fig. 4 is a vertical sectional view through the gas supply pipe and the pipe connected therewith and with the burner showing the operating rod and the form of the valve seated connection between the supply pipe and the pipe leading to the burner. Fig. 5 is a front end view of the valve seated connection. Fig. 6 is a rear end view of the same. Fig. 7 is a transverse sectional view thereof. Fig. 8 is a longitudinal sectional view of the slideable pole which is operated by the gas valve stem

to produce a spark. Fig. 9 is an end view of the housing in which is slidably mounted the rod carrying one of the spark points or contacts. Fig. 10 is an end view of the extension having the ignition chamber and the flame nozzle. And Fig. 11 is a diagrammatic view showing the sparking device in circuit with a battery.

Similar letters of reference refer to similar parts throughout the several views.

Referring to the accompanying drawings: The numeral 1 indicates the gas supply pipe of an ordinary gas range, 2 the burners and 3 the pipes connecting the burners and the supply pipe. The burners shown are of a style in common use and the pipes 3 are integrally connected therewith, their ends which connect with the gas supply pipe, being provided with the usual valved air inlet members 4. The supply pipe is provided with short internally threaded nipples 5 and 6, the nipples 5, receiving packing boxes 7, and the nipples 6, receiving connecting members 8, which are provided with valve seats 9, in their threaded ends, with packing boxes 10 in line with the valve seats, and with chambers 11, which communicate with the valve seats, the forward end walls of said chambers being provided with outlet openings 12, that part of the said connecting member beyond its threaded end being preferably elliptical in cross section to better provide for the packing boxes 10 and chambers 11, as will be understood by reference to Fig. 4.

Each pair of packing boxes 7 and 10, are in axial line, the numbers of such pairs of packing boxes corresponding to the number of burners, as will be understood. As the igniting mechanisms are identical, a description of a single burner and its igniting mechanism will suffice.

A valve stem 12^A passes through the boxes 7 and 10, the outer end of said stem being provided with a knob 13, while its inner end is preferably threaded and enters a threaded aperture in the end wall of a chamber 14, which forms the termination of the pipe 3, and connects the same with the burner.

The valve stem 12^A carries a plug valve 15, which normally rests upon the seat 9, of the connecting member 8, and thus cuts off the supply of gas to the burner.

The packing box 7 includes a gland 16, which is internally threaded and that portion of the valve stem which passes through

the gland is also threaded, so that when the stem is turned in one direction, the valve is moved off of or away from its seat and when turned in the opposite direction, the valve is moved against the seat.

The inner end portion of the valve stem carries a dog 17, of the style shown in Fig. 3, the object of which will be hereinafter set forth. The valve stem and its dog form the 10 operating means for the improved sparking device, which is arranged and constructed in the following manner: The inner wall of the chamber 14 is provided with a threaded aperture 18, into which one end of a tubular housing 19 is screwed. The end of this housing which enters the wall of the chamber carries a threaded plug 20, which is provided with a valve seat 21, and a wall or diaphragm 22, is formed in the housing, 15 which is provided with a central rectangular guideway aperture 23, and with other apertures 24, for the passage of gas. The outer end of the housing is formed with an annular shoulder 25, and a union 26 is slipped 20 over the housing and against the shoulder 25, before the housing is screwed into the wall of the chamber 14. To the outer end of the housing 19 is coupled an extension 27, having an ignition chamber 28, which 25 terminates in a nozzle 29, which curves up and over the adjacent edge of the burner in position to discharge a jet of flame upon the top of the burner, as will be hereinafter set forth. The lower side of the extension 30 has a threaded nipple upon which a cap 30 is screwed, the nipple permitting access to the ignition chamber when the cap is removed.

The union 26 connects the extension 27 to the housing 19, as the nozzle 29 would prevent the screwing of the housing into the wall of the chamber 14, if the extension were an integral part of said housing, as will appear by reference to Fig. 3. The extension is also provided with a wall or diaphragm 31, similar to the diaphragm 22 in the housing 19, which has a rectangular guideway aperture 32, in axial line with the guideway aperture 23 in the said diaphragm 22, and apertures 33, for the passage of gas. In 40 these guideway apertures is slidably mounted a rod 34, which is rectangular in cross section, the forward end of which extends into the ignition chamber. The rear portion of this rod comprises a section 35, which 45 is hinged to the rod so as to normally lie in line with the same, or on a horizontal plane, and the hinge joint permits the section 35 to be swung upwardly only. A blade spring 36 is secured to the section at one end and the other 50 end thereof bears upon the adjacent end of the rod and this spring normally holds the section in a horizontal position, as shown in Fig. 3. The same result is obtained by securing the spring to the rod, its free end 55 bearing upon the hinged section.

The under side of the hinged section 35 is provided with a catch 37, which is adapted to be engaged by the dog 17, on the valve stem 12^A, when the same is turned to admit gas to the burner, whereby the rod 34 is slid forward. The rod is provided with a collar 38, between which and the diaphragm 31 is interposed a coil spring 39, which surrounds the rod 34, and the said rod is provided with a plug valve 40, which is normally held upon the seat 21 by the coil spring 39. The rod 34 has an axial passage 41, which extends from near its rear end to within a short distance from its forward end, and the ends of this passage open 70 out through the under side of the rod, as shown most clearly in Fig. 8. The forward end of the rod is formed with an axial hole in which is secured in any suitable way, a socket member 42 of any suitable non-conducting material and into this socket is screwed a metal spark point or contact 43. A plug 44, of any suitable non-conducting material is screwed into a threaded aperture in the extension 27, in axial line with 75 the rod 34, and into the plug 44 is screwed a spark point or contact 45, the plug 44 being adjustable to move the spark point 45 to the proper position to coöperate with the spark point 43.

The faces of the catch 37 and of the dog 17 are so inclined, that when the stem 12^A is turned, the dog 17 exerts a slight down pull on the hinged section 35, at the same time that the rod 34 is being slid forward. Whereas if the faces of the dog and catch were vertically arranged or inclined in the opposite direction, the pressure of the dog against the catch might swing the section 35 up and the dog would thus escape from the catch without moving the rod forward. The dog is arranged to push the rod forward far enough to cause its spark point 43 to touch the point 45, when the stem 12^A has been given approximately a quarter rotation, and 100 at the same instant the dog escapes the catch and the spring 39 restores the rod to its normal position. Upon reverse rotation of the stem 12^A, the dog engages the catch and lifts the section 35 by which it is permitted to 105 pass the catch.

In admitting gas to the burner, it may be necessary to turn the valve stem a complete rotation or even more, to admit a sufficient flow of gas, but after escaping the catch the 110 first time, the dog will be moved far enough to one side of its operative position by the unscrewing action of the valve stem to be out of line with the catch and will therefore fail to operate the rod after the first 115 forward movement thereof, thus avoiding unnecessary sparking.

Insulated circuit wires A and B, which are preferably bound together in a single insulating wrapper C, are passed in through 120

an opening in the air intake 4 and through the pipe 3 to the adjacent end of the rod 34, where they are inserted in the passage 41, in the said rod, and out through the forward end of the said passage. The ends of the wires are then stripped of their insulation, and the wire A is secured in any suitable manner to the spark point 43 and the wire B is in like manner secured to the spark point 35, the arrangement of the housing and its extension being such as to admit of the wires being easily secured to their respective points. The opposite ends of the wires connected with each sparkers are connected respectively to the poles of a suitable battery or to a plug which may be screwed into an ordinary electric light socket.

In operation, the valve stem 12^A is turned to withdraw the valve 15 from its seat, whereby gas is admitted through the pipe 3 to the burner. Simultaneously therewith the dog 17 engages the catch 36 and moves the rod 34 forward, whereby the valve 40 is moved away from its seat, permitting a flow of gas through the housing. When it reaches the position where its point 43 touches the point 35, a spark is produced by the current passing through the wires A and B, by which the gas in the ignition chamber is ignited and passes out through the nozzle 29, in a jet of flame, which ignites the gas escaping through the perforations in the burner. Simultaneously with the sparking the dog 17 escapes the catch 36, and the rod 34 is thrown back by the spring 39, thereby seating the valve 40 and cutting off the supply of gas from the housing 19.

When the burner is arranged like the right hand burner in Fig. 1 the rod 34 is moved to the left when the valve stem is turned to admit gas and to accomplish this the valve stem must lie beneath the rod 34. When the burner is arranged like the left hand burner in Fig. 1, the rod 34 must be moved to the right when the valve stem is turned to admit gas and to accomplish this the valve stem must lie above the rod 34. To accomplish this it is only necessary to turn the valved connecting member 8, over so that its stuffing box 10 lies uppermost and then connect the pipe 3, the same as in Fig. 4. In this way the valve stem is positioned to lie above the rod 34.

Having described my invention, what I claim as new and desire to secure by Letters Patent, is:

1. In an electric igniting device for gas burners, the combination with a burner of a hollow support attached thereto, having a fixed and a movable contact in circuit with an electric power source, means for admitting gas simultaneously to said burner and to said hollow support, and means connected with the gas admitting means for causing said movable contact to engage said fixed

contact thereby to produce a spark, whereby the gas in said support is ignited and passes out over said burner in a jet of flame, and means for automatically restoring the movable contact to its normal position instantly upon the production of a spark.

2. In an electric igniting device for gas burners, the combination with a burner having a hollow member attached thereto, of means for admitting gas simultaneously to said burner and hollow member, electric igniting means in said hollow member and operable by the gas admitting means, for producing a spark simultaneously with the admission of gas to the burner and means for directing said ignited gas over the top of the burner.

3. In an electric igniting device for gas burners, the combination with a burner having a hollow member, of means for admitting gas simultaneously to said burner and hollow member, electric igniting means in said hollow member comprising a fixed and a movable spark point in circuit with a power source, means connected with the gas admitting means for advancing said movable spark point to contact with the fixed point to produce a spark whereby the gas in said hollow member is ignited and passes out over the top of said burner, and means for automatically restoring the movable spark point to its normal position.

4. In an electric igniting device for gas burners, the combination with a burner having a tubular housing connected therewith, of means for admitting gas to said burner and housing, electric igniting means in said tubular housing comprising a fixed contact and a slidable rod having a contact, circuit wires extending through said slidable rod and connected at one end with a power source and at the opposite ends with the fixed and slidable contacts respectively, means connected with the gas admitting means for sliding said rod to cause its contact to engage the fixed contact thereby to produce a spark to ignite the gas in said housing from whence it issues in a flame above the top of said burner, and means for returning the rod to its initial position.

5. In an electric igniting device for gas burners, the combination with a burner, of electric igniting means connecting therewith, means for admitting gas to said burner, means for admitting a portion of said gas to said igniting means, means connected with the gas admitting means for actuating the igniting means to produce a spark whereby the gas is ignited in the means by which it is admitted to the igniting means, whence it issues in a flame over the top of the burner.

6. In an electric igniting device for gas burners, the combination with a supply pipe, a burner and a pipe connecting the same and the supply pipe, said supply pipe having a

valve seat outlet into the pipe leading to the burner, of a valve for normally closing said outlet, having a stem which extends through the supply pipe and the pipe leading to the burner, the outer end of which carries a knob, while its inner end enters a bearing in said burner, said rod having a threaded connection with the supply pipe; a housing threaded to and communicating with the burner pipe, a rod slideable in said housing, a valve on said rod for normally closing communication between the housing and burner pipe, a dog on said valve stem for sliding said rod simultaneously with the admission of gas to the burner whereby the valve on said rod is moved away from its seat to admit gas to said housing, a contact on said slideable rod and a coöperating fixed contact in the housing in line with the movable contact, said contacts being in circuit with a power source, said dog being arranged to escape the slideable rod when the same has been moved to cause its contact to touch the fixed contact, thereby to produce a spark which ignites the gas in said housing, said housing being arranged to convey the ignited gas over the top of the burner, and a spring for restoring the rod to its normal position simultaneously with its escape from the said dog, whereby its valve closes communication between the housing and the burner pipe.

7. In an electric igniting device for gas burners, the combination with a burner and its supply pipe, of a housing connected to and communicating with said pipe and having a nozzle extending over the adjacent portion of said burner, a fixed and a slideable contact in said housing in circuit with an electric power source, means for admitting gas to the burner and for simultaneously advancing said moving contact into sparking relation with the fixed contact, whereby gas in the housing is ignited and passes out through the said nozzle over the burner, means for pushing the movable contact away from the fixed contact instantly upon the producing of a spark, and means for opening and closing communication between the housing and the burner pipe.

8. In an electric igniting device for gas burners, the combination with a burner and its supply pipe, of a tubular housing leading out of said supply pipe and terminating in a nozzle which extends above the gas burner, a fixed and a movable sparking point in said housing in circuit with an electric power source, means forming a part of the gas admitting means for advancing the movable point into sparking relation with the fixed point, whereby gas in the housing is ignited and passes out of the nozzle over the burner, means for restoring the movable sparking point to its normal position instantly upon the production of a spark, and

means for opening and closing communication between the housing and the said burner supply pipe.

9. In an electric igniting device for gas burners, the combination with a burner and its supply pipe, of a tubular housing leading out of the said supply pipe and terminating in a nozzle which extends over the adjacent portion of said burner, a rod slidably mounted in said housing, having a spark point at its forward end and a spring controlled hinged section at its other end which extends into said supply pipe, a fixed spark point in the housing in line with the movable point, circuit wires extending through said slideable rod and connected with a power source and with the respective spark points, a valve on said slideable rod for normally closing communication between the housing and burner supply pipe, said housing having a valve seat therefor, a catch on the hinged section of the said rod, a valve stem extending through said pipe, a dog on said stem for engaging said catch to slide said rod to bring its point in sparking relation with the fixed point, said dog being adapted to escape the catch simultaneously with the production of a spark, a spring for instantly reversing the slideable rod, a gas supply pipe connected with the burner pipe and having a valve seated connection and a valve on said valve stem for normally closing the seat in said connection, the slideable rod being moved simultaneously with the admission of gas to the burner.

10. In an electric igniting device for gas burners, the combination with a gas supply pipe, a burner and a pipe leading therefrom, of a connecting member uniting the supply pipe and the burner pipe having a valve seat, a packing box in line therewith and a chamber communicating with the valve seat, having an outlet which forms communication with the burner pipe, a stem extending through the supply pipe and through the valve seat and packing box in said connecting member and through the burner pipe to the burner, a valve on said stem which normally closes the seat in said connecting member, a housing leading out of the burner pipe and terminating in a nozzle which extends over the adjacent portion of the burner, an electric sparking device in said housing and means on the valve stem for operating said sparking device simultaneously with the admission of gas to the burner, and means of opening and closing communication between the housing and burner pipe, said valve stem having a threaded connection with the said gas supply pipe.

11. In an electric igniting device for gas burners, the combination with a burner of electric igniting means attached thereto,

- means for admitting gas simultaneously to the burner and to the igniting means and means connected with the gas-admitting means for operating the said igniting means 5 simultaneously with the admission of gas to the burner.
12. In a device as specified, the combination with a burner and its supply pipe, a housing leading from the pipe, a separable 10 nozzle connected to the housing and extending over the adjacent portion of the burner, a fixed spark member in the housing, a slide- able spark member in line with a fixed member, said members being in circuit with an 15 electric power source, a valve on said slide-
- able member for normally closing communication between the housing and pipe, and a spring for holding said slideable member in valve closing position, of means for admitting gas to the burner and means connected 20 with the gas admitting means for advancing said slideable member into sparking relation with the fixed member simultaneously with the admission of gas to the burner.

In testimony whereof I affix my signature 25 in presence of two witnesses.
